UNITED STATES PATENT OFFICE

WALTER E. NAYLOR, OF CHICAGO, ILLINOIS, ASSIGNOR TO THE BEARDSLEY & PIPER COMPANY, OF CHICAGO, ILLINOIS, A CORPORATION OF ILLINOIS

MACHINE FOR HANDLING MOLDING SAND

Application filed February 11, 1927. Serial No. 167,490.

The present invention relates to machines for handling molding sand.

In factories in which molding machines of the rotary projector type are used, it is desirable to provide means for separating the scrap and the like from the sand as the sand is being delivered to the projector, and the primary object of the invention is to provide an improved construction in which a magnetic separator is disposed to receive and act upon the sand as it is discharged by the elevator and being delivered into the conveyor which feeds the projector.

Other objects of the invention will be apparent from a consideration of the following detailed description.

The invention consists in the several novel features hereinafter set forth and more particularly defined by the claims at the conclusion hereof.

In the drawings: Fig. 1 is a side elevation of a portable molding machine embodying the invention. Fig. 2 is a vertical section through the magnetic separator and its co-acting elements. Fig. 3 is a horizontal section taken on the line 3—3 of Fig. 2. Fig. 4 is a vertical longitudinal section taken through the magnetic separator.

The invention is exemplified in connection with a portable sand projector of the general type which is exemplified in United States Letters Patent granted to Beardsley and Piper March 7, 1922, No. 1,408,796, and comprises a wheeled truck-frame adapted to travel on tracks in the molding room floor. The frame comprises sides 10 and is provided with wheels 27 and traction wheels 21 having toothed peripheries to mesh with racks in rails set into the molding room floor.

The molding machine on the truck comprises a jib 44 pivoted to swing horizontally on a post 42 carried by the truck-frame 35; an arm 45 which is pivoted at 44^a on the outer end of jib 44 so it may swing horizontally relatively to said jib; a sand projector 46 on the outer end of arm 45; an electric motor 47 mounted on said arm and connected to drive the rotor of the projector; a vibratory conveyor chute 48 mounted to swing with jib 44 and into which sand is delivered by a

vertically extending elevator; mechanism for vibrating the chute mounted to swing with jib 44 and contained in a housing 49; and an endless feed belt 45^a which is mounted to swing with arm 45, receives sand from the chute 48 and delivers it to the projector and is driven by the motor 47. The vibratory chute 48 is provided with a screen or riddle 48^a which causes the sand to be distingrated, as the result of the vibration to which it is subjected in its passage through the screen. The chute and mechanism associated therewith may be substantially of the construction set forth in Patent No. 1,408,493 dated March 7, 1922, to which reference may be had for a more detailed description.

The elevator which operates to supply a stream of sand from a pile on the floor to the head of the truck, comprises an endless chain 56 having a series of buckets 61 thereon. The sand will be delivered to the elevator, which is centrally disposed, either by a cross-conveyor, as exemplified in Patent No. 1,408,796, or by other suitable means, as exemplified in an application for Letters Patent filed by the aforesaid Beardsley and Piper January 11, 1926, Serial No. 80,447. The chain 56 is driven by a sprocket 57 on a horizontally extending shaft 58 and passes around an idler sprocket 59 at the upper end of a standard 60. The sprocket 59 is rotatably mounted on a shaft 61 which is carried by a pair of levers 61^a. The latter are fulcrumed on the standard and are connected to springs 61^b to put the chain 56 under sufficient tension to keep it taut at all times. The elevator is driven from a motor mounted on the truck-frame, as exemplified in the aforesaid Patent No. 1,408,796, so that the elevator will be constantly driven while the molding machine is in use to elevate sand from the floor or a point adjacent the floor to an elevation from which it may be discharged into the conveyor for delivering the sand to the projector.

The standard 60 is hollow, so that the downwardly travelling reach of the elevator will be enclosed thereby. At the upper end of said standard, there is formed a discharge hood or chute 60^a to confine the sand dis-

charged by the elevator buckets. An inclined wall 60^b and an adjustable plate 60^c form a hopper to catch the sand and scrap discharged by the elevator.

A separating drum comprising a cylinder 5 70 and sides 71 is mounted under the constricted discharge opening between wall 60^b and plate 60^c, and this drum is constantly rotated to discharge the material in regulated quantity from the hopper. The discharge side of the drum is disposed above the receiving end of the conveyor chute 48. The walls of the hood 60^a are extended downwardly at the sides of the drum to enclose the sides thereof and to form sides for the hopper. The drum is mounted to rotate around a stationary shaft 72 and its heads 71 are provided with hubs 73 which are journalled in bearings 74 and 75. Each of the bearings is separately formed from the standard 60 and is secured to an angle iron 76 secured to one of the outer faces of the side walls of the hood 60^a. One of the hubs 73 of the drum extends beyond its bearing 75 and has secured thereto a sprocket-wheel 77. A shaft 78 is mounted in a bracket 79 which is fixed to the front face of the standard 60. A sprocket wheel 80 is secured to shaft 78 so that it will be driven by the upwardly travelling reach of the elevator chain. A sprocket 81 is fixed to shaft 78 and is connected to drive the sprocket 77 by a sprocket-chain 82. The bearing 74 is extended to receive one end of the shaft 72, and the latter is locked against rotation by a set screw 83. A stationary magnet, consisting of a support or core 85 and suitable windings 86, is fixedly secured to the central portion of the stationary shaft 72. Conductors 88 for the windings of the magnet extend through the stationary shaft 72 and thence to the terminals of the windings. The magnet is shaped to be effective upon the scrap throughout an arc of approximately 180° and is positioned adjacent that portion of the drum with which the descending sand contacts. The lower portion of the magnet projects a sufficient distance beyond the point of discharge of the sand to release the scrap and discharge the same separately into a chute 89 at the back of the standard. It is to be noted that the sprocket 81 is considerably smaller than the sprocket 77. As a result of this arrangement the periphery of the drum moves at a substantially slower speed than that at which the sand is discharged from the buckets and against the drum, and consequently the drum does not accelerate the movement of the sand and scrap but retards the same so as to render the magnet efficient in separating the scrap from the sand. It is also to be noted that the hood and hopper are arranged so that the buckets discharge the loads of sand directly against the top part of the drum. 60 In practice, it has been found that by ar-

ranging the various parts so that the sand is discharged in this manner, the separator is rendered more efficient in operation for the reason that the scrap is impacted against the drum so that it forces its way into direct contact therewith.

In operation, the sand will be discharged from the elevator buckets into the hood 60^a and so that it is projected directly against the upper part of the drum. The drum, which rotates constantly during the operation of the elevator, will carry the material from the hopper and deflect the sand into the conveyor 48. The scrap or metal, responsive to magnetic influence and within the influence of the magnet in the drum, will adhere to the drum so it will be carried beyond the receiving end of the conveyor and released over the chute 89 and thus separated from the sand.

The invention exemplifies a molding machine in which a magnetic separator is interposed between the elevator and the feeding mechanism which feeds the sand to the projector and by which the metal particles and scrap will be separated from the sand and separately discharged. The drum around the stationary magnet is driven by power derived from the elevator, so that no separate driving mechanism is necessary. The sand is discharged over the vibratory conveyor. The separating mechanism is simple in construction and may be produced at a low cost.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a machine of the character described, the combination of a column having rotary supporting means at the upper end thereof, an upwardly extending endless sand elevator supported on said means and comprising a series of buckets and an endless chain, a hood on the column and adjacent said supporting means to receive the sand from the elevator, said hood having a discharge outlet at the lower end thereof, a rotatable drum under said outlet, a conveyor under the drum into which the sand will be deflected by the drum, means operated by the chain for driving the drum, and a stationary magnet inside of the drum formed to hold metallic material on the drum so it will be discharged beyond the conveyor.

2. In a machine of the character described, the combination of a column having rotary supporting means at the upper end thereof, an upwardly extending endless sand elevator supported on said means and comprising a series of buckets and an endless chain, a hood on the column and adjacent the supporting

means to receive the sand from the elevator, said hood having adjustable means at the lower end thereof forming a restricted outlet, a rotatable drum under the outlet, a conveyor under the drum into which the sand will be deflected by the drum, a sprocket operated by the chain for driving the drum, a stationary shaft carried by the column and around which the drum is rotatable, and a magnet inside of the drum, fixed to the shaft and formed to hold metallic material on the drum so it will be discharged beyond the conveyor.

3. In a machine for handling molding sand, the combination of a supporting structure, a magnetic separator mounted on said structure and comprising a rotatable drum, a bucket elevator for the sand, said elevator operating to discharge the sand forcibly and in successive loads against the top part of the drum, and mechanism for rotating the drum.

4. In a machine for handling molding sand, the combination of a supporting structure, a magnetic separator mounted on said structure and comprising a rotatable drum, means for delivering the sand to the top part of the drum, including a series of buckets and an endless chain, and mechanism connected to be driven by the chain for rotating the drum.

5. In a machine for handling molding sand, the combination of a supporting structure, a magnetic separator mounted on said structure and comprising a rotatable drum, means adapted to be driven for delivering the sand directly and forcibly against the top part of the drum, and means for conjointly driving the sand delivery means and the drum, said driving means being operable to rotate the drum so that the periphery thereof will move at a substantially slower speed than that at which the sand is discharged from the delivery-means.

45 6. In a machine for handling molding sand, the combination of a supporting structure, a magnetic separator comprising a rotatable drum, an elevator for delivering the sand forcibly and in successive loads against the top part of the drum, including a series of buckets and an endless chain, and mechanism connected to be driven by the chain for rotating the drum, said mechanism being operable during drive of the elevator to rotate 50 the drum so that the periphery thereof will move at a substantially slower speed than that at which the sand is discharged from the buckets.

Signed at Chicago, Illinois, this 21st day
60 of January, 1927.

WALTER E. NAYLOR.
